UNITED STATES PATENT OFFICE.

JOHN H. MEREDITH, OF SURATTSVILLE, PRINCE GEORGE'S COUNTY, MD.

CAR-COUPING.

SPECIFICATION forming part of Letters Patent No. 259,032, dated June 6, 1882.

Application filed November 10, 1881. (No model.)

To all whom it may concern:

Be it known that I, JOHN H. MEREDITH, a citizen of the United States of America, residing at Surattsville, Prince George's county, 5 State of Maryland, have invented certain new and useful Improvements in Car-Couplers; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This invention relates to improvements in car-couplers upon which Letters Patent were granted to me February 17, 1880, in which I employed hooks placed in a horizontal position, which opened automatically and closed upon 20 the coupling-pin of the next car when the cars were brought together.

The object of the present improvement is to enable the hooks to be raised and lowered and adjusted and fastened at any desired height in 25 the draw-head without going between the cars, in order that cars of different heights may be coupled together automatically and without danger to the person who does the work. My application for Letters Patent for this part of 30 my invention was allowed April 4, 1881. I have now made a further improvement, consisting in a locking device to prevent the hooks from opening after they have closed upon the coupling-pin of the next car. All of the above-named

35 objects I attain by the mechanism illustrated in the accompanying drawings, in which—

Figure 1 is an end elevation of a freight-car, and Fig. 2 is a side elevation of part of a freight-car, showing different parts of raising and lowering and locking devices. Fig. 3 is a detached view of a part of the raising and lowering device. Fig. 4 is a detached plan view of the raising and lowering and locking arrangements taken from the bottom. Fig. 5 is a side elevation of a part of a passenger-car, showing a 40 part of the raising and lowering device.

F is a crank, something in the form of a bell-crank. It turns upon its shaft F', to which is attached at right angles the arm F''. This arm 45 F'' has an elbow, and at its lower extremity there is a hook, f, which enters a staple, l.

This staple l is secured to a plate, I. The plate I is attached to a vertical rod or pin, P. The rod P is so arranged as to have an upward and downward movement by elevating or depressing the crank-arm F. The plate m is secured to this pin or rod P, as well as to the coupling-hooks J J, by the pivots n n, and also to the staple l.

E is a curved plate, having ratchet-teeth cut 60 on one of its edges. It may be attached to the body of the car, or in any other suitable position, such as the rails of the platform in passenger-cars. It is intended to secure the crank-arm F, in any position that may be required. 65

K K are draw-heads. B is a hand-wheel attached to shaft D. S is the coupling-pin. C is a ratchet-wheel and pawl. H is a pulley.

G is a pulley attached to shaft D. When the crank-arm F is turned to the right and downward the hooked point f of the arm F'' will have an upward motion and lift the plate L, together with the rod P, as well as the coupling-hooks J J, to a higher position. When high enough to engage and couple with the 70 next car the arm F must be released. When this is done it will engage in the teeth of the ratchet-plate E, and thus be held in the proper position to allow the cars to couple; but should the arm F be down, and it is desired to couple 75 with a lower car, the arm F must then be raised to the desired height, and this will lower the coupling-hooks J J, and the arm F, upon being released, will be held in its proper position by 80 the plate E.

85 The locking device is shown in Figs. 1, 2, 4. It consists of a plate or wedge, Y, having a casting or guide, Z, in which it slides freely up and down, so as to be raised or lowered. When raised it occupies a position between the coupling-hooks J J, fitting snugly between the two and just touching both of them, in such manner as to prevent the rear ends of the hook-bars J J from approaching each other, and in this way locking them, so that in any strain upon the 90 hooks when the cars are going around a curve, or from any other cause, they will not open, and thus release the coupling-pin and allow the cars to become separated from each other, as they would otherwise be apt to do upon any 95 sudden strain or when heavily loaded. The wedge or plate Y is raised and lowered by 100

- means of the lever U, operating upon the shaft U', to which it is attached at right angles, and which has an arm, V, pivoted to a link, W, which is attached to the wedge Y by a hinged joint. I do not confine myself to this exact construction, as it might be varied without departing from my invention. The pivoted hooks R R' are intended to hold the lever U in place either when locked or unlocked.
- 10 I claim as my invention—
1. In a car-coupling, the levers or bell-cranks F F' F'', in combination with staple l and plate I, as described, and for the purposes set forth.
  2. The combination, in a car-coupling, of the levers F F' F'', hook f, staple l, and ratchet-plate E, substantially as shown and described, and for the purposes set forth.

3. A locking plate or wedge arranged to be raised and lowered between the coupling hook bars of a car-coupling, as described, and for the purposes set forth.

4. In a car-coupling, the combination of locking plate or wedge Y, operating-lever U, shaft U', arm V, link W, and casing or slide Z, substantially as shown and described, and for the purposes set forth.

In testimony whereof I affix my signature in presence of two witnesses.

JOHN H. MEREDITH.
